No. 710,428.

Patented Oct. 7, 1902.

H. P. COLBY.

RUNNING GEAR.

(Application filed Mar. 20, 1902.)

(No Model.)

UNITED STATES PATENT OFFICE.

HARLAN P. COLBY, OF GRAND RAPIDS, MICHIGAN.

RUNNING-GEAR.

SPECIFICATION forming part of Letters Patent No. 710,428, dated October 7, 1902.

Application filed March 20, 1902. Serial No. 99,100. (No model.)

To all whom it may concern:

Be it known that I, HARLAN P. COLBY, a resident of Grand Rapids, in the county of Kent and State of Michigan, have invented 5 certain new and useful Improvements in Running-Gear; and I do hereby declare the following to be a full, clear, and exact description of the invention, such as will enable others skilled in the art to which it appertains to 10 make and use the same.

My invention relates to an improved running-gear for vehicles, the object of the invention being to provide improvements of this character which will be comparatively 15 cheap to manufacture, light, yet extremely strong and durable and able to withstand at all times the necessary strains thereon.

With this object in view the invention consists in certain novel features of construction 20 and combinations and arrangements of parts, as will be more fully hereinafter described, and pointed out in the claims.

In the accompanying drawings, Figure 1 is a plan view illustrating my improvements. 25 Fig. 2 is a side view of one of the bars. Figs. 3 and 5 are enlarged views of the ends of the gear, and Fig. 4 is a bottom plan view of the casting 4.

1, 2, 3 represent three bars arranged as shown 30 and secured at their converging rear ends in a casting 4. This casting 4 comprises three cups 4, located at an angle to each other, and the bars are secured thereby, the rear ends of these cups being inclined, as shown, and brace- 35 rods 5 are secured beneath the bars, as will now be explained.

One end of the rod 5 is screw-threaded and passed through a recess in the end of a bar and through a hole in the end of cup 4, and 40 a nut 6 is screwed thereon against the end of the cup. The opposite end of rod 5 is flattened and bent around the cross-bar 7 and over the bar 3 and secured thereto by a bolt 7^a and nut, as shown, and the rod projects 45 between its ends below a cross-bar 8, thus forming a truss to withstand great strains on the center of bar 3 and prevent possibility of breaking until an enormous pressure sufficient to snap rod 5 is applied. While I have 50 described but the construction of rod 3, it is to be understood that this description applies alike to bars 1 and 3, as both bars are

constructed alike. It will be seen that with my improvements these rods 5 can be adjusted, by means of nuts 6, to insure the proper tension on the bars 1, 2, 3, and thereby insure great strength to the gear on which one-half of the 55 fifth-wheel is secured.

A great many slight changes might be resorted to in the general form and arrangement of the several parts described without departing from the spirit and scope of my invention, and hence I would have it understood that I do not limit myself to the precise construction set forth, but consider myself at 60 liberty to make such slight changes and alterations as fairly fall within the spirit and scope of my invention.

Having fully described my invention, what I claim as new, and desire to secure by Letters 70 Patent, is—

1. In a running-gear, the combination with a series of diverging bars and a casting connecting said bars at one end, of a brace-rod 75 for each diverging bar, each brace-rod secured at one end to said casting and the other ends of said brace-rods embracing the ends of the bars farthest removed from said casting, and secured thereto.

2. In a running-gear, the combination with 80 a series of diverging bars and a casting connecting said bars at the end where they converge, of a cross-bar connecting divergent ends of the bars, and a brace-rod for each diverging bar, one end of each brace-rod 85 embracing the cross-bar and the end of the adjacent diverging bar, and adjustably secured at the other end to said casting.

3. In a running-gear, the combination with 90 a series of diverging bars, a casting connecting said bars where they converge, a cross-bar connecting the divergent ends of diverging bars, and an intermediate cross-bar connecting said divergent bars, of brace-rods for said divergent bars, each brace-rod secured at one 95 end to the casting and bearing at an intermediate point against said intermediate cross-bar, the other end of each brace-rod embracing the other cross-bar and the end of the adjacent diverging bar and fixed to the latter. 100

4. A running-gear composed of three longitudinal bars converging at one end, a cross-bar at the diverging ends of said longitudinal bars, another cross-bar below and between

the ends of said longitudinal bars, a casting connecting the converging ends of said longitudinal bars, and brace-rods secured to the respective ends of the longitudinal bars engaging one of said cross-bars and passed around the other.

5. A bar for a running-gear having a metal cup on one end, a brace-rod bent around the other end of the bar and secured thereto by 10 a bolt or screw, a device spacing the rod from the bar between its ends, said bar having a recess at its end and the metal cup having a hole to receive the screw-threaded end of said brace-rod, and a nut on the brace-rod screwed 15 home against the end of the cup.

6. In a running-gear, the combination with a series of diverging bars, of a casting having a series of radial pockets or cups in which 20 said bars are seated, a cross-bar connecting the divergent ends of the said bars, an intermediate cross-bar connecting said diverging bars and brace-rods for said diverging bars, each brace-rod secured at one end to the casting

and bearing at an intermediate point against 25 said intermediate cross-bar, the other end of each brace-rod embracing the other cross-bar and the end of the adjacent diverging bar and fixed to the latter.

7. A running-gear composed of three longitudinal bars converging at one end, a cross-bar at the divergent ends of said longitudinal bars, another cross-bar below and between the ends of the longitudinal bars, a casting having radial pockets or cups into which the convergent ends of said bars are inserted and 30 35 brace-rods secured to the respective ends of the longitudinal bars, engaging one of said cross-bars and passed around the other.

In testimony whereof I have signed this specification in the presence of two subscr- 40
ing witnesses.

HARLAN P. COLBY.
